SHAPING DEVICE FOR HATS

Martin L. Nattenheimer, Chicago, Ill.

Application July 18, 1936, Serial No. 91,252

2 Claims. (Cl. 223—24)

This invention relates to shaping devices for hats and more particularly to shaping accessories used with the standard shaping block to effect a variety of shapes and forms.

5 One of the objects of my invention is to provide shaping accessories which can be secured interchangeably to the conventional blocking crown for the purpose of shaping hats to any desired form.

10 Another object is to provide a shaping accessory which can be attached to the standard shaping blocks in a very simple manner without altering the block itself.

15 Another object is to provide a shaping accessory which lends itself to positioning on any part of the crown of the standard shaping block.

Due to the ever continuous changing of styles in ladies' hats it is necessary for a manufacturer of such to provide blocking units to correspond 20 to the size and shapes of the styles desired. Since each individual style must be made in several sizes and a complete blocking unit provided for every size, it can be seen that cost of such procedure is a very important factor in manufacturing overhead.

25 It is therefore the purpose of my invention to provide auxiliary forms which can be secured interchangeably to the conventional shaping block for the purpose of effecting any design, 30 shape or size without the necessity of using a variety of independent integral blocking units for each of such change of style or size. These auxiliary forms are shaped so that their outer surfaces correspond to the style desired and the 35 inner surfaces are shaped complementally to the crown of the standard shaping block. The latter permits the auxiliary form to be positioned on any part of the crown of the block, to provide modifications of the style of such form.

40 Referring to the drawing, it will be seen that

Figure 1 is a perspective view showing the conventional shaping blocks with one form of my auxiliary shaping unit secured thereto;

45 Fig. 2 is a cross section of the upper portion of Fig. 1;

Fig. 3 is a plan view of another form of auxiliary shaping unit;

Fig. 4 is a cross sectional view of Fig. 3 taken 50 on line 4—4 showing particularly the inner convex surface of the shaping unit;

Fig. 5 is a perspective view of another form of shaping unit;

Fig. 6 is a view of another form of shaping unit 55 showing a modified form of construction;

Fig. 7 is a view showing the manner of securing the fastening pins to the shaping units.

As shown in Fig. 1, I make use of the conventional skull crown shaping block 10 which is provided with the usual curved surface 11. To this 5 surface I attach any one of the auxiliary shaping forms shown in the figures or any other form corresponding to a style desired. Referring particularly to Figs. 1 and 2 it will be seen that the shaping accessory shown therein is formed like 10 a paraboloid, while that shown in Figs. 3 and 4 is shaped ovaly with a convex outer surface.

The shaping accessory shown in Fig. 5 is formed to simulate a triangle while that of Fig. 6 is shaped to that of a hyperboloid. While only 15 a few of the shaping accessories are shown it will be understood that other forms of shaping units corresponding to various styles of hats desired can be used.

The auxiliary forms represented generally by 20 numeral 12 have outer surfaces 13 shaped to conform to the different styles to which the hats are to be molded, and have inner concave surfaces 14 shaped complementally to the top of the crown skull shaping block so that they can be positioned anywhere on the crown of said block. Each of these forms 12 is provided with a plurality of pins 15, preferably 3 in number, whose ends are threaded as at 16, for permanent securing to the form, and whose opposite ends 30 are shaped as at 17 to permit simple attachment to the shaping block. It will be noted that due to the size and shape of the pins no damage will be done to the crown by the continuous attachment and detachment of the 35 shaping forms. As will be seen these shaping forms can be interchangeably secured and positioned on top of the shaping block in any one of a number of different positions to form a complete blocking unit. The form is detached merely by pulling it away from the block.

In Fig. 6 I show a modified form of construction of a shaping accessory in which the inner concave surface is provided with a rubber lining 45 18 to provide a close contact between the shaping accessory and the crown of the block. This is used in cases where the surfaces are not strictly complementary.

It will be understood that various types, sizes and shapes of auxiliary forms can be made and 50 used without departing from the spirit and scope of my invention.

I claim:

1. In combination with a skull crown block having a substantially spherical surface, a hat 55

shaping accessory comprising a body portion having an outer surface of predetermined shape conforming with the particular style of hat to be shaped, said accessory having an inner concave shaped surface to cooperate with the spherical surface of the block, whereby said accessory is attachable in any one of a number of positions on said block, the outer surface of the accessory cooperating with the exposed spherical surface of the block to produce a complete distinct shaping contour.

2. In combination with a skull crown block having a substantially spherical surface, a hat shaping accessory comprising a body portion having an outer surface of predetermined shape con-

forming with the particular style of hat to be shaped, said accessory having an inner concave shaped surface to cooperate with the spherical surface of the block and means for detachably connecting said body portion of the accessory to the crown portion of the block, comprising a plurality of pin members attached to the concave inner surface of the accessory and adapted for insertion in the block, whereby the accessory may be mounted in any desired position throughout the spherical surface of the block, the outer surface of the accessory cooperating with the exposed spherical surface of the block to produce a complete distinct shaping contour.

MARTIN L. NATTENHEIMER. 15
